DESIGN FOR A FLUORESCENT LIGHTING
FIXTURE OR SIMILAR ARTICLE

Thomas G. Beckett, Dallas, Tex.

Application September 14, 1946, Serial No. 133,325

Term of patent 7 years

(Cl. D48—23)

To all whom it may concern:

Be it known that I, Thomas G. Beckett, a citizen of the United States, residing at Dallas, in the county of Dallas and State of Texas, have invented a new, original, and ornamental design for a Fluorescent Lighting Fixture or Similar Article, of which the following is a specification, reference being had to the accompanying drawing, forming part thereof.

Figure 1 is a bottom perspective view of a fluorescent lighting fixture or similar article showing my new design.

Figure 2 is a bottom plan view thereof,

Figure 3 is an end elevational view, and

Figure 4 is a transverse sectional view taken on line 4—4 of Figure 1.

I claim:

The ornamental design for a fluorescent lighting fixture or similar article, substantially as shown.

THOMAS G. BECKETT.
